UNITED STATES PATENT OFFICE.

JAMES T. COWLEY, OF MINOT, MASSACHUSETTS, ASSIGNOR TO THE LAMSON COMPANY, OF BOSTON, MASSACHUSETTS, A CORPORATION OF NEW JERSEY.

CONVEYER FOR NEWSPAPERS AND THE LIKE.

1,248,623.

Specification of Letters Patent.

Patented Dec. 4, 1917.

Application filed May 1, 1916. Serial No. 94,567.

To all whom it may concern:

Be it known that I, JAMES T. COWLEY, a citizen of the United States, residing at Minot, in the county of Plymouth and State 5 of Massachusetts, have invented certain new and useful Improvements in Conveyers for Newspapers and the-like, of which the following is a specification.

This invention relates to conveyers for 10 newspapers and the like and has for one of its objects the substantial elimination of all tendency of the apparatus to smear or smudge freshly printed matter.

Another object of the invention is to so 15 construct the flexible article carrying elements of the mechanism as to largely obviate the trouble arising from breakage of such elements when the apparatus is in use, by the exercise of moderately careful super- 20 vision thereof; the flexible elements being themselves caused to give warning of impending rupture thereof rather than to let go, so to speak, without any signs of impending trouble.

25 Another object of my invention is to so constitute said elements that they may make contact with the freshly printed articles at a plurality of spaced points along their length, where operatively engaged with 30 such articles, and maintain such contact at said points during the transmission of each given article without change occurring in the spacing of said points with respect to each other; said elements being substantially 35 inelastic in the direction of their length and preferably having sufficient tensile strength to permit of their use to themselves drive the various guiding pulleys over which they pass.

40 These and other objects of my invention will be hereinafter referred to and the novel means and combinations of elements whereby said objects may be attained will be more particularly pointed out in the claims ap- 45 pended hereto.

In the accompanying drawing which forms a part hereof and in which like reference characters designate like parts throughout the several views, I have ex- 50 plified a preferred embodiment of my invention; but as I am aware of various changes and modifications which may be made therein without departing from the spirit of said invention, I desire to be limited only by the scope of said claims.

Referring to said drawing:

Figure 1 is a side elevation of a news- paper conveyer.

Fig. 2 is a top view of the same, drawn to an enlarged scale. 60

Fig. 3 is a front elevation of the lower portion of said conveyer.

Fig. 4 is an enlarged front detail view of the take up mechanism in said conveyer.

Fig. 5 is a fragment of a preferred type 65 of flexible element which constitutes one of the article engaging and supporting devices of said conveyer.

Fig. 6 is a similar view of a modification; and 70

Fig. 7 is a detail section taken on line VII—VII of Fig. 3.

The conveyer shown is adapted for use as an elevator or as a lowerator, depending upon the direction in which the flexible ele- 75 ments are driven; but for convenience of description it will be considered as an ele- 80 vator and arrows have been applied to indicate the direction of travel of certain of the parts.

The uprights 1 support staggered rolls 2 between which the opposed article supporting portions of the flexible elements 3—3' travel; this staggered arrangement of pres- 85 sure rolls being of course known.

The elements 3 in the construction shown are six in number, and extend around pul- 90 leys or sheaves 4 at the top of the elevator and downwardly in parallelism toward and around the idler pulleys 5 upon the rear side of the tensioning device, thence up and around the idlers 6 upon said side of said device, and then down and around the lower pulleys 7, whence they return upwardly 95 again to the pulleys 4.

Similarly, the elements 3', of which there are also six, as shown in Fig. 3, pass down- 100 wardly from pulleys 8, around idlers 5 and 6 upon the left-hand side of the conveyer shown in Fig. 1, and thence around pulleys 100 9 and back to the upper front pulleys 8.

The tensioning device comprises a series of spring drums 10, one for each flexible element 3—3', said drums being mounted in brackets 11 and each having a rope or cord 105 12 which tends to draw the corresponding slide-bracket 13 of an idler 5, down toward its drum. This obviously places the corre- 110 sponding element 3 or 3', as the case may be, under a determined tension.

- The rolls 2 are preferably grooved, as at 2', for the reception of the elements 3—3' and are frictionally driven directly by the latter when the apparatus is in operation.
- 5 To this end the elements 3—3' are made of materials sufficiently strong to substantially oppose elongation thereof when thus driving any of the pulleys or idlers over which they pass; this being highly desirable not only in that no separate drives for such pulleys or idlers are required; but, further, and of greater importance, such inextensible or inelastic elements constructed as herein-after described, tend less to smear or smudge 10 the ink of freshly printed newspapers, in the direction of the length of said elements where in engagement with said newspapers, than is the case with elastic cords or belts of any description.
- 15 20 Now as to the preferred construction of the article-carrying elements 3—3'. As shown in Fig. 5, said elements comprise a substantially inextensible core or cord 3^a of cotton cable or the like. Closely wound, 25 braided or otherwise fastened to the exterior of this core is a covering or partial covering of material which does not tend to absorb ink. This material may be treated fiber or the like or it may be metal, either 30 wound tightly on as shown in Fig. 5, or braided on as per Fig. 6. It further is preferably so formed or mounted on its core as to present to the freshly printed newspapers or the like a series of contact points rather 35 than an unbroken surface, so that when contact is made, even if the ink of a letter be slightly wiped, the letter as a whole is still legible. In one way the braided wire or fiber formation is perhaps the best for this 40 reason, but as the wire-wrapped cord shown in Fig. 5 is substantially as good and can be manufactured by simple mechanism, it is to be preferred.

In any case however, it is most desirable 45 that the distances between the adjacent points of contact of the flexible wire-wrapped cable or the like and a freshly printed newspaper, be maintained so long as the paper is being supported at these 50 points; since if the cord were elastic and the points could hence separate from and approach each other as they happened, for example, to pass a guiding pulley, then the freshly printed matter would be apt to be 55 streaked at such places, which of course tends to spoil the appearance of the sheet.

On the other hand, if the cord 3^a alone were to be used, it would tend to soak up the moist ink and smear or smudge the papers delivered to it thereafter.

60 The preferably composite paper gripping elements embodied in my newspaper conveyer, however, permit of the presentation to the freshly printed papers to be conveyed, 65 of surfaces which are impervious to the wet

ink, being non-absorbent in character and moreover very limited in extent, while these small contacting surfaces or points remain at substantially fixed distances apart.

The preferred covering or wrapping for 70 the core is soft, Swedish iron wire, whereby is obtained an exceedingly flexible structure which passes freely and durably about pulleys even as small as three inches in diameter. In Fig. 5, two strands 3^b are wrapped 75 onto the core 3^a, while in Fig. 6 the covering 3^c is braided on.

The papers coming from the printing-press 14 travel in overlapped relationship upon the narrow belts 15, of which there are 80 four in the construction shown. These belts pass around pulleys 16, mounted on a common shaft 17, which also carries the pulleys 9 above referred to, and pulleys 18 around which pass short "angle belts" 19.

85 These latter extend from their respective pulleys 18 to idlers 20, thence to idlers 21, and back to pulleys 18, which drive said angle belts. These angle belts receive the papers from the belts 15 and turn them up 90 toward the ascending sides of the elements 3' preparatory to their reception between said sides and the corresponding ascending portions of the elements 3.

95 At the top of the elevator, a set of short angle belts 22, which pass around pulleys 23 and 24, co-act with a set of belts 25, which pass around pulleys 26, tensioning idlers 27, and preferably fixed idlers 28, to divert the ascending overlapped papers toward the left, as viewed in Fig. 1, and thence obliquely upwardly toward and around the pulleys 23 for delivery to the horizontally traveling belts 29.

100 The upper and lower horizontal belts 29 and 15 are supported by rollers 30 carried by the usual side boards 31—31', respectively; and the belts 15 may drive all of the others. To this end I prefer to provide fiber strips 32 in the bottoms of the grooves 110 33 of the pulleys 9, 7, etc., on which ride the elements 3—3'; as shown in Fig. 7 wherein one of the pulleys 9 is partly broken away to illustrate this feature. To insure that the elements 3 shall travel with the 115 same linear velocity as the opposed elements 3', I prefer to provide meshed gears 34 and 35, of the same pitch diameters, upon the shafts 36 and 37 which respectively carry the pulleys 4 and 8 around which 120 travel said elements 3—3'; while a third gear 38, of equal pitch diameter, is meshed with the gear 34 and maintains the speed of the angle belts 22 and horizontal belts 29 equal to that of the elements 3—3' and belts 25; gear 38 being upon the shaft 39 which carries the pulleys 23 aforesaid, and the pulleys 40 of the belts 29.

125 From the time that the newspaper 41, or the like, leaves the horizontal belts 15, until 130

it rides out on the upper horizontal belts 29 from under the angle belts 25 which maintain the overlapped arrangement and thereby what is termed the "count" of the 5 papers,—the belts or elements between which such paper is successively gripped are at all times moving with substantially the same velocity, and what is more, owing to the inelasticity of the elements 3—3', all parts of 10 said elements are at all times moving with substantially equal velocity; there being no stretching or opening up of said elements as the overlapped and sometimes quite thick 15 masses of papers pass the successive rolls 2, with consequent ink-streaking tendency.

Finally, it may be pointed out that the 20 novel tensioning device shown in Figs. 1 and 4 is especially well adapted to maintain a uniform tension in the respective elements 3—3'. Herein, the brackets or frames 13 are slidably mounted on rods 42 which extend between transverse bars or plates 43, attached to the uprights 1 in any suitable manner, and each of these frames 13 moves 25 independently of the others to maintain the corresponding flexible element under the tension desired. Especially where the flexible elements are quite long is such a tensioning device to be preferred to the more 30 commonly used weights, since the inertia of the latter tends to render them sluggish in taking up abrupt or vibratory like changes in tension, whereas in the present device the tension in the individual elements 35 is at all times practically constant.

In conclusion, I desire to point out a further advantage which the elements 3—3' possess over known devices which have heretofore been used in newspaper conveyers,— 40 to wit, the warning given by such an element, after it has been in use a long time, that rupture thereof is imminent. If one of the paper engaging strands 3^b, for example, of a given element breaks, the device 45 as a whole is not likely to give way all at once, but rather the remaining strand or strands and also the core will hold. The broken ends of the wire or the like will be very apt to be observed in ample time to 50 permit of a simple repair being made which necessitates but a short stoppage of the apparatus. On the other hand, let us assume that, after the device has been in use a long while, the core breaks at some point. 55 Here, the strands will simply unravel or pull out and the break will become apparent, and yet the broken ends are held near together and the element as a whole will not jump free of its pulleys to the detriment 60 of the papers being conveyed or to perhaps cause the ruptured cable or the like to snarl up with the uninjured cables. The non- 65 resilient soft iron wire or the like of which the strands 3^b are preferably composed, in a case such as that last described is greatly

to be preferred to, for example, spring or resilient wire, since the inelastic strands even when merely wrapped on to the core, tend to cling to the latter and unravel but little therefrom when the core or said 70 strands break, whereas, if the strands be themselves resilient they will, under the circumstances described, tend to spring outwardly away from the core, the diameter of their turns increasing until said turns are 75 no longer individually in tension.

Having thus described my invention what I claim is:

1. In a conveyer for freshly printed newspapers and the like, the combination of a 80 plurality of substantially inextensible opposed flexible elements portions of which travel together under tension and at the same speed from one level to another, to carry said newspapers therebetween in overlapped relationship, means to co-act with said elements to prevent slippage of said newspapers with respect to each other, and means to drive said elements, said elements being of composite construction and comprising strands of flexible material each secured to a flexible core to normally space the latter away from the newspapers in course of conveyance and to frictionally engage said papers at spaced points, the surfaces of said strands being impervious to the wet ink of said papers. 90 95

2. In a conveyer for freshly printed newspapers and the like, the combination of a plurality of opposed narrow flexible elements paper gripping portions of which travel together under tension and at the same speed from one level to another to carry said newspapers therebetween, means to co-act with said elements to prevent slippage of said newspapers during transit, and means to drive said elements, said elements being substantially inextensible and having on all sides thereof paper engaging surfaces which are impervious to the wet ink 100 105 of said papers and contact with each of the latter only at spaced points, said impervious surfaces being present on all sides of said elements as aforesaid to insure the presentation of proper surfaces to the articles 110 115 being carried, regardless of any twist or torque in said elements about the longitudinal axes thereof.

3. In a conveyer for freshly printed newspapers and the like, the combination of a 120 plurality of substantially inextensible opposed flexible elements portions of which travel together under tension and at the same speed from one level to another, to carry said newspapers therebetween in overlapped relationship, means to co-act with said elements to prevent slippage of said newspapers with respect to each other, and means to drive said elements, said elements being of composite construction and com- 125 130

prising strands of inelastic material each secured to a flexible core to normally space the latter away from the newspapers in course of conveyance and to frictionally engage said papers at spaced points, the surfaces of said strands being impervious to the wet ink of said papers.

In testimony whereof I have affixed my signature, in the presence of two witnesses.

JAMES T. COWLEY.
